UNITED STATES PATENT OFFICE.

CHARLES C. BAUER AND FRANK H. FRANKENBERG, OF PUEBLO,
COLORADO.

CURTAIN OR LAMBREQUIN SUPPORT FOR WINDOWS.

SPECIFICATION forming part of Letters Patent No. 392,774, dated November 13, 1888.

Application filed April 10, 1888. Serial No. 270,183. (No model.)

To all whom it may concern:

Be it known that we, CHARLES C. BAUER and FRANK H. FRANKENBERG, of Pueblo, in the county of Pueblo and State of Colorado, have 5 invented a new and useful Improvement in Curtain or Lambrequin Supports for Windows, of which the following is a description.

Figure 1 is a front elevation, and Fig. 2 a vertical transverse section, of a window with 10 our invention applied thereto.

The object of our invention is to provide a support for curtains, lambrequins, or other window-hangings which is so connected to the upper sash that when the latter is lowered for 15 the purposes of ventilation the curtain or lambrequin support is moved away from its position in front of the opening to allow a free and unobstructed ventilation; and it consists in providing such support and combining it with 20 the upper sash, whereby the above result is obtained and the curtain or lambrequin is also held in proper position, as hereinafter more fully described.

In the drawings, A A' represent the upper 25 and lower sash, which slide in the usual way in the window-frame B, being balanced by cords and weights, which cords pass over pulleys in the box frame. On the inner face of the window-frame, on each side, is pivoted at 30 a the upright metal bars C C, which at their upper ends are wider and provided with notches, slots, and journal-bearings b for the curtain-rollers and lambrequin - poles, and which upper ends rest, when the bars are vertical, at the top of the window and in the proper and usual position for the curtain and lambrequin supports.

D D are link-bars, of which there are two, one on each side. One end of each of these 35 bars is jointed to the upright bars near the

middle, and the other end is jointed to a staple or hinge-plate on the upper sash. By this construction it will be seen that whenever the upper sash is lowered the thrust of the link-bars D D projects the supporting-bars C C of 45 the curtains downwardly and away from the window, giving a free passage for air.

To keep the curtains from falling out of position in this movement, and also to hold them smoothly in place when the window is closed, 50 an offset, a', is formed on the lower ends of the supporting-bars, and on the ends of the offset is secured the rod E, which rests outside the curtains.

Having thus described our invention, what 55 we claim as new is—

1. The bars C C, having bearings at their upper ends for the curtain or lambrequin rods, combined with links pivoted to the same and adapted to be connected with the upper sash, 60 as and for the purpose described.

2. The combination, with the window-frame and the uppersash, of supporting-bars pivoted to the sides of the frame and having bearings for the curtain or lambrequin poles at the top 65 and links connecting these supporting-bars to the upper sash, as described, for simultaneous automatic action.

3. The bars C C, pivoted to the window-frame and having bearings for the curtain or 70 lambrequin poles at the top, and a connecting-rod, E, at the bottom, in combination with the window frame and sash and the links connecting the sash to the supporting-bars, as set forth.

CHARLES C. BAUER.

FRANK H. FRANKENBERG.
